ATTORNEYS.

UNITED STATES PATENT OFFICE.

EDWIN GEBHARDT, OF CINCINNATI, OHIO, ASSIGNOR TO THE GEBHARDT BROTHERS COMPANY, OF CINCINNATI, OHIO, A CORPORATION OF OHIO.

BRACELET.

Application filed April 18, 1924. Serial No. 707,524.

My invention relates to bracelets to be worn for ornaments, and more particularly to a device in which the main bracelet is a flexible backing member onto which the decorative elements are mounted in a simple manner and connected together in one or more units to provide the amount of jewels or decoration desired, and in which the decorative units may be increased from time to time.

It is the object of my invention to provide a series of sliders on a bracelet of ribbon or the like, which have a simple means for securing them together and which will when placed on the wrist, stay firmly in place, without chance of becoming dislodged until the wearer by properly directed action desires to remove them. The sliders may then be set with jewels without chance of being lost, and as many of them secured together on the ribbon, as may be desired, or as may correspond with the sum which the wearer desires to spend.

It is my object to provide a structure which is simple to manufacture, and easy to mount, and in which the mode of attachment of the parts together is not apparent to the observer.

I accomplish these objects by that certain construction and arrangement of parts to be hereinafter more specifically pointed out and claimed.

In the drawing:

Figure 1 is a front elevation of the devices forming my invention.

Figure 2 is a rear elevation of the same.

Figure 3 is a section on a larger scale taken on the line 3—3 of Figure 1, showing the inside of the ribbon up.

Figure 4 is a side elevation on a larger scale.

Figure 5 is a plan view of a connector piece.

Figure 6 is a like view of the connector piece with the jewel plate removed.

Figure 7 is a plan view of an intermediate slider piece.

Figure 8 is a section on line 8—8 of Figure 7 showing the jewel plate in place.

I have shown a bracelet or ribbon, having a slider 1 secured to one end of the ribbon 2, and the other end of the ribbon is secured to a pin 3. The slider 1 has a loop 1^a over which the one end of the ribbon is sewed.

The slider is moved along to effect adjust-

ment of the diameter of the bracelet, in the usual manner, and the stiffened end is trapped by the ornaments. Some other mode of forming the bracelet could be used, and adjusting it to size, and while I prefer the form shown, as working in with my improvements effectively, I do not insist upon it.

The ornaments are in the form of sliders. I have shown three, but any number can be hitched together, like links in a chain, all the way around the ribbon, so long as they do not interfere with the mode of getting the bracelet on and off from the wrist.

There are connector sliders, and intermediate sliders in the form shown. The connector sliders have a top 4, and turned under flanges 4^a, 4^b, which engage over the ribbon and hold the slider in place thereon.

The connector sliders have tongues 5 which are formed into channels or hooks at both ends of the sliders, and one or more tiny posts or pins 6 are set into the outer lips of the channels. The flanges 4^a at the sides of the device are formed with projections 5^a.

The intermediate sliders are formed with tops 7, and flanges 7^a, 7^b, for engaging over the ribbon, and having bent down edges 8, and holes for the tiny posts. The flanges 7^a are formed with indentations 8^a to engage around the projections 5^a, and form a close fit.

The tops of the plates may be unitary with the same, or may be in part, inserts, of more precious metal, set into spaces left in the tops, as will be obvious without illustration. The tops will usually be set with jewels, as indicated at 9.

In placing the sliders on the ribbon, the ribbon is placed between the flanges, and the intermediate plates are tipped so that the turned down edges enter the channels in the connector plates, and the tiny posts enter the holes in said intermediate plates. The intermediate plates are then tipped back to lie parallel with the connector plates.

When so connected any pull on the parts will fail to dislodge them, and a direct separation by pushing up or down on the connected parts, will not separate the interengaging hooks 5 and 8.

The interconnected projections and indentations 5^a and 8^a, prevent this separation and the ribbon itself tends to prevent it.

The only way to disconnect the sliders is to loosen or take off the bracelet, and tip the unconnected ends of the intermediate sliders outwardly, thereby rocking the projections and indentations 5^a and 8^a, out of interengagement and then lifting the intermediate plates away from the tiny posts.

It is evident that a purchaser of the bracelet may buy but one connector slider, and 10 may thereafter purchase several intermediate sliders, and may then purchase more connectors or intermediate sliders. Also the intermediate sliders may be formed as connectors at one end and intermediates at the 15 other.

Where the ribbon has a filled end, it will be held from running through the decorative slider, which is furthest from the size adjusting slider 1, since the added thickness 20 will prevent its passing underneath the flanges of the slider adjacent to it.

In Figures 6, 7 and 8, I have illustrated a way of making up the two kinds of sliders out of small stampings, over which covers 25 of desired patterns of precious metal and set with precious stones, may be mounted.

The intermediate sliders are formed as a four sided frame 20, with the slider tongues 21, bent over at the side edges thereof. The 30 connector sliders have frame-like bodies 22, with slider tongues 23 and flanges 24 at the two sides, turned up to act as hooks, under the side bars of the frames of the intermediate sliders. If small projections 25 are 35 left on the ends of flanges 24, they will serve as the posts 6, in the first described form. The side bars of frames 20 will have notches 26 for partly receiving the projections 25.

The pieces so formed will be sold as findings and over them are placed covers, indicated in Figure 8, providing a decorative top. The covers have bodies 26^a, and turned

down flanges 27, which snap over the beads formed by the tongues 21 or 23. The jeweler will set the covers in place and then hold 45 them fast with solder. The plates will clear the hooks formed by the flanges 24, and if the projections 25 are used the fittings may have holes in them for clearance. The frame 20, with a top secured upon it, presents the 50 same general appearance, and has the same functions as the intermediate sliders first noted. The same is true for the connectors.

Having thus described my invention, what I claim as new and desire to secure by Letters Patent, is:—

1. A bracelet comprising a flexible, encircling band, and a plurality of detachable sliders thereon, formed as a connector slider, and an intermediate slider, the connector slider having tongues at the ends formed with channels, and the intermediate slider having tongues at the ends formed to engage in said channels, and posts mounted on the 60 tongues of one slider, and the other slider having holes to engage over said posts, along the line of connection between said channels. 65

2. A bracelet comprising a flexible, encircling band, and a plurality of detachable sliders thereon, formed as a connector slider, and an intermediate slider, the connector slider having tongues at the ends formed with channels, and the intermediate slider having tongues at the ends formed to engage in said channels, and posts mounted on the 70 tongues of one slider, and the other slider having holes to engage over said posts, along the line of connection between said channels, said sliders having projections and 75 indentations at the sides thereof, respectively, 80 adapted to come into engagement when the tongues are hooked together and the posts are in the holes.

EDWIN GEBHARDT.
